UNITED STATES PATENT OFFICE.

DAVID STOLL, OF BROOKLYN, NEW YORK.

DESIGN FOR A METAL BORDER STRIP FOR BOWLS OR SIMILAR ARTICLES.

Application filed March 20, 1923. Serial No. 5,542. Term of patent 7 years.

To all whom it may concern:

Be it known that I, DAVID STOLL, a citizen of the United States of America, residing at Brooklyn, Kings County, State of New York, have invented a new, original, and ornamental Design for a Metal Border Strip for Bowls or Similar Articles, of which the following is a specification, reference being had to the accompanying drawing, forming part hereof, in which—

Fig. 1 illustrates a face view of a metal border strip for ornamenting a bowl or similar article showing my new design, and

Fig. 2 is an edge view thereof. Said border strips are manufactured and sold as independent articles of manufacture.

I claim:

The ornamental design for a metal border strip for bowls or similar articles as shown.

Signed at New York city, N. Y., this 16th day of March, 1923.

DAVID STOLL.
